WOBBLE TAIL FOR FISH LURES

George A. Smail, 36 N. Hazelwood, Youngstown, Ohio

Filed May 1, 1964, Ser. No. 79,770

Term of patent 14 years

(Cl. D31—4)

FIGURE 1 is a bottom elevational view of a wobble tail for fish lures, showing my new design;

FIGURE 2 is a top elevational view thereof;

FIGURE 3 is a side elevation thereof; and

FIGURE 4 is a perspective thereof; the broken line showing is for illustrative purposes only.

I claim:

The ornamental design for a wobble tail for fish lures, as shown and described.
